ELECTRICAL CABLE

George A. Seeley, Baltimore, Md., assignor to
 Western Electric Company, Incorporated, New
 York, N. Y., a corporation of New York

Application September 11, 1936, Serial No. 100,271

3 Claims. (Cl. 173—265)

This invention relates to electrical cables and more particularly to a coaxial cable in which one conductor is substantially a hollow metallic cylinder enclosing another metallic conductor of 5 smaller diameter spaced from and supported in the cylinder by spacing members of insulating material.

It may be desirable in some instances, to lay up 10 two or more such coaxial conductor pairs in a compound cable, either alone or with other conductor units of other types. In such a case, the coaxial units will be stranded or intertwined together, which may present some difficulties because of the inherent torsional rigidity of the 15 cylindrical outer conductor of a coaxial pair.

Coaxial conductor pairs also are frequently used to form an outgoing and return circuit for 20 an alternating electrical current of high frequency. It is therefore particularly essential that the inner surface of the outer conductor, which faces and is nearest to the inner conductor, shall be smooth, continuous and free from irregularities so far as may be.

Objects of the present invention are to provide 25 a coaxial conductor pair which shall be simple in structure, easy to manufacture, of relatively low torsional rigidity at least in one direction of possible twist, and having an outer conductor inherently smooth within.

30 One embodiment of the invention contemplates a coaxial conductor having any suitable form of inner or axial conductor such as a solid wire, hollow strand, or compound strand, with a plurality of spacing members of insulating material 35 thereon, and with an outer conductor of cylindrical form on the spacing members, the outer conductor being a strip or tape of metal formed longitudinally into a cylinder and having its edges meeting and held in place by integral means exterior to the cylinder, but preferably such as to 40 permit of longitudinal displacement of the abutted edges of the tape relatively to each other, while preventing any radial displacement of the edges.

45 Other objects and features of the invention will appear from the following detailed description of one embodiment thereof taken in connection with the accompanying drawing in which the same 50 reference numerals are applied to identical parts in the several figures and in which

Fig. 1 is a broken view in side elevation of a part of a coaxial conductor pair constructed in accordance with the invention;

55 Fig. 2 is an end view thereof;

Fig. 3 is a side view on a reduced scale of a portion of the pair after being twisted;

Fig. 4 is an end view thereof;

Fig. 5 is a plan view of a portion of a tape to be formed into an outer conductor, and

Fig. 6 is an end view thereof.

In the embodiment of the invention herein disclosed, a coaxial conductor pair comprises an inner or axial conductor 10, a plurality of slotted spacing disks 11, 11 mounted on the inner conductor at intervals therealong, and a cylindrical outer conductor 12 resting on the peripheries of the disks 11, 11 to be supported on and spaced from the inner conductor thereby. The inner conductor herein disclosed is preferably a smooth 15 solid circularly cylindrical wire of copper, but may be of other metal or of other form if desired, e. g., a cylinder, a plurality of associated strands, or any other practicable form. The disks 11, 11 20 may be thought of as molded or formed or cut from any suitable insulating material, e. g., artificial resin, rubber, cellulose plastic, or the like and may have any form suitable for the purpose.

The outer conductor 12 is a strip or tape of suitable material such as copper, bronze, aluminum or other appropriate conductive substance, formed over the peripheries of the disks 11, 11 into a cylinder supported thereon, the cylinder being in this instance of circular cross-section, although if desired it may in some cases be non-circular. 25 The strip is formed along both edges thereof with spaced, integral, outwardly projecting teeth 14, 14. These teeth 14, 14 are offset by about the thickness of the tape toward that side of the tape which forms the outer surface of the cylindrical 30 outer conductor. The true edges 15, 16 of the tape being abutted to form a seam 17, the teeth 14 35 of each edge overlie the other edge, so that the teeth of each edge hold the other edge down.

If in the manufacture of the tape shown in Figs. 40 5 and 6, the teeth are cold worked (as by being swaged while being cut with a punch and die, cutting rolls, or the like), they may, in the process of being formed into the cylindrical conductor, be more or less deeply imbedded into the material 45 of the opposite edges, thus still more securely interlocking the edges along the seam 17, which however, increases the torsional rigidity of the formed conductor.

However in the embodiment herein disclosed, 50 it is desired to have the outer conductor torsionally flexible with respect to a specific amount of left hand twist, and laterally flexible after being twisted. Hence the teeth 14, 14 are so proportioned and so disposed relatively to each other 55

that when the conductor is first formed as shown in Figs. 1 and 2, with the seam 17 disposed along a straight geometrical element of the cylindrical form of the conductor, each tooth of one edge is substantially abutted laterally of itself against one corresponding tooth of the other edge, those of edge 15 being just to the left of those of edge 16 as seen in Fig. 1. These abutted pairs of corresponding teeth are further spaced apart along the seam 17.

When the conductor pair is now twisted, as for example in being laid up with one or more similar pairs in a compound cable, the edges 15 and 16 slide along each other and the teeth take positions such as shown in Figs. 3 and 4, as the seam 17 is changed from a straight line to a helix. Thus the teeth may be distributed at substantially equal intervals along the helical seam of the twisted unit.

In some instances, the teeth may preferably be formed to stand at spaced intervals along the straight seam. The unit may then be twisted either way.

Furthermore if the pair is not to be twisted, but it is desired to have the seam helical, the tape may be wrapped spirally instead of being formed longitudinally over the disks 11, 11, in which case the teeth of the tape will be originally located to fall as shown in Fig. 3.

A cable as shown in Fig. 3, or comprising units such as shown in Fig. 3, will have much greater flexibility both in torsion and in flexure than an analogous structure with the edges of the tape welded, soldered or immovably interlocked, yet neither edge can lift above the other radially to produce any internal ridge or protuberance to harm the desired electrical properties of the pair.

It will be clear that the embodiment of the invention herein disclosed is only illustrative and may be modified and departed from in many ways without departing from the spirit and scope of the invention as pointed out in and limited solely by the appended claims.

What is claimed is:

1. In a coaxial conductor pair the combination with an axial conductor of an outer hollow con-

ductor therearound and comprising a metal tape formed into a tube with the edges of the tape abutted together to form a seam, each edge of the tape having projections thereon overlying the outer side of the other edge, the widths of the spaces between consecutive projections on either edge being greater than the widths of the projections on the other edge and the projections on either edge overlapping the other edge between consecutive projections of the other edge, the parts being so proportioned and arranged that when the conductor pair is twisted each edge and its projections are free to slide along the other edge to provide torsional flexibility, while the seam cannot open radially.

2. In a coaxial conductor pair the combination with an axial conductor and spacing members thereon of an outer hollow conductor therearound and comprising a metal tape formed into a tube with the edges of the tape abutted together to form a seam, each edge of the tape having projections thereon overlying the outer side of the other abutting edge, the widths of the spaces between consecutive projections on either edge being greater than the widths of the projections on the other edge and the projections on either edge overlapping the other edge between consecutive projections of the other edge, the parts being so proportioned and arranged that when the conductor pair is twisted each edge and its projections are free to slide along the other edge to provide torsional flexibility, while the seam cannot open radially.

3. In a coaxial conductor pair the combination with an axial conductor and spacing members thereon of an outer hollow conductor therearound and comprising a metal tape formed into a tube with the edges of the tape abutted together to form a seam, each edge of the tape having projections thereon overlying and slidable on the outer side of the other edge, so that when the conductor pair is twisted each edge and its projections are free to slide along the edge to provide torsional flexibility, while the seam cannot open radially.

GEORGE A. SEELEY.
